CLAIM

The ornamental design for a multi position freestanding training bag, as shown and described.

DESCRIPTION

FIG. 1 is a top front perspective view of the multi position freestanding training bag showing our new design;

FIG. 2 is a front perspective view thereof;

FIG. 3 is a back view thereof;

FIG. 4 is a right side view thereof;

FIG. 5 is a left side view thereof;

FIG. 6 is a top view thereof, shown on an enlarged scale relative to FIGS. 1-5; and,

FIG. 7 is a bottom view thereof, shown on an enlarged scale relative to FIGS. 1-5.

The broken lines in FIGS. 1-5 are included for the purpose of defining a portion of the multi position free standing bag that forms no part of the claimed design. The detail shown in broken lines along the inner perimeter in FIG. 6 likewise forms no part of the claimed design.
